UNITED STATES PATENT OFFICE

HOMER D. DUFALUT, OF EASTHAMPTON, MASSACHUSETTS, ASSIGNOR OF TWO-TENTHS TO ALDERIC FUGERE, TWO-TENTHS TO EUCLIDE FUGERE, TWO-TENTHS TO ADAM BOUCHER, ONE-TENTH TO HENRY BERNIER, AND ONE-TENTH TO HIRAM BERNIER, ALL OF EASTHAMPTON, MASSACHUSETTS

OIL BURNER

Application filed August 19, 1931. Serial No. 558,136.

The invention aims to provide a new and improved oil burner of the type in which oil is gasified in a retort and discharged into gas channels from which it is in turn discharged into spaces between perforated cylinders, provision being made for mixing air with the gas.

Burners of the general type above mentioned necessarily embody gas-conducting ports from the retort to the gas channels or grooves, and prior to initial heating of the burner base, these ports of course conduct oil instead of gas. The ports must be thoroughly cleaned from time to time in order to obtain efficient burner operation, and while the invention provides a burner which requires only a minimum amount of cleaning, it is a further object of said invention to so locate the ports as to facilitate cleaning thereof whenever advisable.

With the foregoing in view, the invention resides in the novel subject matter herein-after described and claimed, description being accomplished by reference to the accompanying drawing.

Fig. 1 is a vertical sectional view through a burner constructed in accordance with my invention.

Fig. 2 is a top plan view of the burner base, the wicks shown in Fig. 1, being omitted.

Fig. 3 is a horizontal sectional view substantially on line 3—3 of Fig. 1.

Fig. 4 is a detail vertical sectional view on line 4—4 of Fig. 3 showing the preferred shape of the ports.

The construction disclosed has proven to be efficient and desirable from all standpoints and is therefore preferred, it being understood however that even though said construction will be herein specifically described, minor variations may be made.

The burner base B is of circular form and is substantially flat, said base being formed with a central air-conducting opening 5

which is open at both its upper and lower ends and occupies about one-third of the diameter of the base. Between the opening 5 and the peripheral edge 6 of the base B, is an annular air-conducting slot 7 which is open 50 at both the upper and lower sides of said base. Between this slot 7 and the opening 5, there is an annular retort groove 8 and a gas groove 9. Between this slot 7 and the edge 6 of the base B, is another gas groove 55 10. Both this groove 10 and the groove 9 are much narrower than the retort groove 8, and all of said grooves open through the upper side of the base B. While the grooves 9 and 10 remain upwardly open, a closure ring 11 is 60 provided to close the upper side of the groove 8, except when cleaning the burner.

Four webs 12 and 13 span the air-conducting slot 7 and are integral with adjacent walls of the grooves 9 and 10. These webs 65 unitarily connect the inner and outer concentric portions of the burner, and the webs 12 have portions of gas-conducting ports 14 formed therein. Each port 14 is straight and leads from the retort groove 8 to the gas 70 groove 9 and then through the web 12 to the gas groove 10, and as seen in Figs. 2 and 3, each port 14 is substantially tangential to the retort groove 8. This relation of ports and groove, together with the width of the latter 75 (8) are of great advantage when the ports must be cleaned, for it is an easy matter to enter a cleaning tool into the ports 14, through the ends of the latter which communicate with said groove 8.

A plurality of perforated metal cylinders 15, 16, 17 and 18 rest upon the base B, the latter being appropriately shouldered to properly support said cylinders. The inner cylinder 15 is in communication with the 85 air-conducting opening 5 and is provided at its upper end with a closure 19. The cylinders 15 and 16 provide an annular space 20 communicating with the gas groove 9, cylinders 16 and 17 provide a similar space 21 90

communicating with the air-conducting slot 7, and the cylinders 17 and 18 provide a space 22 communicating with the gas groove 10. The spaces 20 and 22 are open at their upper ends but the space 21 is closed by an appropriate ring 23.

To initially heat the burner to gasify the oil fed thereto through the inlet 24, wicks 25 are preferably located in the grooves 9 and 10. When the oil is turned on, some of it runs from the retort groove 8 through the ports 14 into the grooves 9 and 10, thereby saturating the wicks 25, so that by lighting these wicks, the burner will be initially heated. As soon as the proper heat has been attained, the oil in the retort groove 8 and the other grooves, becomes gasified, and the gas discharges into the annular spaces 20 and 22 and here mixes with the air flowing from the interior of the cylinder 15 and from the space between the cylinders 16 and 17. The mixture of gas and air is so thorough that an extremely blue flame is obtained even when the oil is being fed with such rapidity that the flame reaches an unusual height above the burner.

The burner may be used for cooking stoves or heating stoves and may embody only one unit such as that herein disclosed, or a plurality of said units having their bases B suitably connected. 26 on the drawing denotes portions of a bracket secured to the base B to support the latter, and this bracket may also be secured to the base of another unit, if desired.

I claim:—

1. An oil burner comprising a substantially flat circular base having a central air-conducting opening therethrough, said opening occupying substantially one-third of the diameter of the base, said base being provided with an annular air-conducting slot therethrough between said opening and its peripheral edge, said base being provided around said opening with a retort groove and with a gas groove between said retort groove and said slot, said base having another gas groove between its peripheral edge and said slot, both of said gas grooves being narrower than said retort groove and upwardly open, a closure for the upper side of said retort groove, webs spanning said slot, said base having passages from said retort groove to said gas grooves extending through said webs, said passages being substantially tangential to said retort groove to facilitate cleaning and said retort groove being provided with an oil inlet; concentric perforated cylinder resting on said base and providing annular spaces which communicate with said air-conducting slot and said gas grooves, the innermost cylinder being in communication with said air-conducting opening, a closure for the upper end of said inner cylinder, and a closure for the

cylinder-defined spaced above said air-conducting slot.

2. A burner base having a relatively wide annular retort groove, relatively narrow annular gas grooves around said retort groove, an air-conducting slot between said gas grooves, webs spanning said slot, and straight gas-conducting passages extending from said retort groove through said webs to said gas grooves, said passages being substantially tangential to said retort groove to facilitate cleaning of said ports. 75

In testimony whereof I affix my signature.
HOMER D. DUFAULT.
